CLAIM

The ornamental design for a road tubeless bicycle rim, as shown and described.

DESCRIPTION

FIG. 1 is a front, right isometric view of a road tubeless bicycle rim showing my new design (the rear, left isometric view, being identical, is not shown);

FIG. 2 is a front elevation view thereof (the top plan, bottom plan, and rear elevation views, being identical, are not shown);

FIG. 3 is a left side elevation view thereof (the right side elevation view, being identical, is not shown);

FIG. 4 is a sectional view thereof, taken at cut line 4-4 of FIG. 3; and

FIG. 5 is a sectional view thereof, taken at cut line 5-5 of FIG. 3;

FIG. 6 is a front, right isometric view of a road tubeless bicycle rim showing my new design (the rear, left isometric view, being identical, is not shown);

FIG. 7 is a front elevation view thereof (the top plan, bottom plan, and rear elevation views, being identical, are not shown);

FIG. 8 is a left side elevation view thereof (the right side elevation view, being identical, is not shown);

FIG. 9 is a sectional view thereof, taken at cut line 9-9 of FIG. 8; and,

FIG. 10 is a sectional view thereof, taken at cut line 10-10 of FIG. 8.

Elements of the road tubeless bicycle rim depicted using broken lines are intended to illustrate the environment of the claimed design and form no part of the claimed design.
